United States Patent Office.

DANIEL J. ROSS, OF HAVRE DE GRACE, MARYLAND.

Letters Patent No. 98,302, dated December 28, 1869.

IMPROVEMENT IN PROPELLING BOATS.

The Schedule referred to in these Letters Patent and making part of the same.

To all whom it may concern:

Be it known that I, DANIEL J. ROSS, of Havre de Grace, in the county of Harford, and State of Maryland, have invented a new and useful Improvement in Propelling Boats; and I do hereby declare that the following is a full, clear, and exact description thereof, which will enable others skilled in the art to make and use the same, reference being had to the accompanying drawings, forming part of this specification.

This invention relates to a new and useful improvement in propelling boats through the water, more especially designed to be applied to small boats, or those which are usually propelled by oars, and consists in driving a propeller-wheel at the stern of the boat, by means of a cord and pulleys, by a crank or cranks, turned by hand, as will be hereinafter more fully described.

In the accompanying plate of drawings—

Figure 1 represents a longitudinal side view, with the side of the boat broken away, to show the driving-apparatus.

Figure 2 is a top or plan view.

Similar letters of reference indicate corresponding parts.

A is the boat.

B is a propeller-wheel, on the end of a shaft, C, which passes through the stern, after the manner of the ordinary propeller-wheel shaft.

D represents a pulley or band-wheel on the propeller-shaft.

E represent stands, which are properly fastened together, and are supported on the bottom of the boat.

F is a crank-shaft, supported by the stands E, upon

which (between the stands) there is another pulley or band-wheel, G, which stands at right angles with the pulley D, as seen in the drawing.

These pulleys are grooved, and a round band is used, so that, although it makes a quarter turn, to fit the position of the pulleys, there will be no danger of its running off the pulleys.

H is the operator's seat.

I is the driving-band.

To propel the boat, the operator or boatman takes hold of the cranks J J, and revolves the pulleys G, and the propeller-wheel, by means of the band I.

This is a direct application of power to the boat, and is much more steady and effective than when the same power is applied by means of oars.

K is the rudder.

L is the tiller-bar, which is connected by means of cords m m, with foot-levers n n, so that the boatman, while he turns the cranks with his hand, may operate the levers n, and steer the boat with his feet.

It will be seen that the power of two men may be applied to the cranks, if desired.

Having thus described my invention,

I claim as new, and desire to secure by Letters Patent—

In combination with the boat A, propeller-wheel B, and shaft C, the pulleys D and G, and band I, when arranged and operated substantially as and for the purposes set forth.

DANIEL J. ROSS.
